Inventor:

George M. Graham,
by Robert P. Burns
Attorney.

UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

REINFORCED CONCRETE FLOOR AND CEILING.

No. 888,999.

Specification of Letters Patent.

Patented May 26, 1908.

Application filed October 17, 1907. Serial No. 397,850.

To all whom it may concern:

Be it known that I, GEORGE M. GRAHAM, a citizen of the United States of America, and a resident of Chicago, in the county of Cook and State of Illinois, have invented certain new and useful Improvements in Reinforced Concrete Floors and Ceilings, of which the following is a specification.

This invention relates to a method of forming the floors, or other like substantially horizontal portions of the reinforced concrete structure which forms the subject matter of my former patent No. 865,490 dated Sept. 10, 1907. And the present improvement has for its object to provide a simple, efficient and economical method whereby a reinforced concrete floor or the like, with the properties of great strength and lightness, is produced, all as will hereinafter more fully appear.

In the accompanying drawings:—Figures 1, 2 and 3, illustrate the progressive steps in the present method, beginning with the reinforcing skeleton structure and ending with the finished floor section or unit.

Referring to the drawings, 1 represents the opposed members of a border frame of round tubing, around which are wound continuous wrappings of wire to form the upper and lower skeleton centers 2 and 3 therefor, and in conjunction with said border frame constitute the skeleton reinforcing portion of a reinforced concrete floor or other like part of a building; and in which construction the individual wire strands comprising the said upper and lower wire skeleton centers 2 and 3 are adapted to assume a common and uniform tension and bear in an even and uniform manner the normal load imposed upon the frame as a whole, and so afford a very light and strong structure, as set forth in detail in my aforesaid prior patent No. 865,490, of Sept. 10, 1907.

4 is a perforated lathing sheet supported a distance away from the upper skeleton wire center 2, by a series of suspension links 5, of varying lengths, and so that the perforated lathing will have a dished form in the initial step of the present system, as shown in Figs. 1 and 2 of the drawing and as fully set forth in my aforesaid patent.

6 is a temporary mold plate or board secured to the under side of the lower skeleton

wire center 3, by suspension loops or other like means adapted to support said plate or board in parallel relation and a short distance beneath the lower skeleton wire center 3 aforesaid.

In the present method, the respective upper and lower skeleton wire centers 2 and 3 will initially have the flat and undished form illustrated in Fig. 1. Fine concrete material is dropped from above, and descending through the mesh of the upper center 2 and its attached lathing 4, accumulates upon the mold plate or board 6, and around and upon the lower center 3 to form the ceiling portion of the floor. The weight or stress of such concrete mass imposes a dished form on the lower center 3 and mold plate or board 6.

Coarse concrete material is then introduced from above and is stopped by lathing 4 to accumulate thereon, and around and upon the upper center 2 to form the floor proper. The superior stress or load of such coarser mass of concrete is adapted to remove the previously existing dished form of the lower center 3, above set forth, and in turn impart a dished form to the upper center 2 and at the same time remove the initially dished form of the lathing before set forth, and as illustrated in Fig. 3.

In the preferred construction, the ends of the lathing 4 adjacent to the tubular frame members or girders 1, will be turned down, to form intermediate spaces 7 for the reception of a mass of concrete to wholly inclose said members or girders 1, and as illustrated in Fig. 3.

Having thus fully described my said invention what I claim as new and desire to secure by Letters Patent, is:—

The herein described method of forming hollow reinforced concrete floors in which the reinforce is formed by wires wound around a border frame of round tubing to provide upper and lower skeleton wire centers with perforated lathing secured to the upper section, with a movement of the one section effecting a corresponding movement of the other section, such method involving the preliminary introduction from above of a fine concrete, the stoppage of the same by a temporary flexible mold plate attached to the lower center to effect an accumulation of the concrete around and upon said center, the

subsequent introduction from above of a
coarse concrete and the stoppage of the same
by perforated lathing attached to the upper
center to effect an accumulation of such con-
crete upon and around the upper center, and
draw the lower skeleton wire center into a taut
and flat condition, substantially as set forth.

Signed at Chicago Illinois, this 2nd day of
October 1907.

GEORGE M GRAHAM.
